UNITED STATES PATENT OFFICE

ERNST WEBER-STIERLIN, OF ZURICH, SWITZERLAND

STRETCHER

Application filed January 30, 1928, Serial No. 250,442, and in Switzerland February 17, 1927.

This invention relates to stretchers and more particularly to stretchers of the kind having two longitudinal poles each consisting of two parts coupled together for use but 5 easily separated for transport, said poles carrying a fabric or the like support and being spaced by stays capable of being locked or clamped in position in such a manner that the stretcher can be divided into two parts 10 for transport or storage, the said parts being coupled together when the stretcher is required for use. The main object of the invention is to provide a stretcher of the type described which can be quickly arranged for 15 use with a minimum of manipulation.

A further object is the provision of automatic means to secure and lock the stays and the poles in their respective positions to form a rigid but very light stretcher. 20 I attain these and other objects by arranging a supporting leg on each of the four longitudinal pole parts so as to be capable of folding, the means for spacing the longitudinal poles being attached to the supporting 25 legs of the longitudinal pole parts.

Moreover the longitudinal pole parts are interconnected by folding or collapsible stays attached to the supporting legs, each stay being provided with means, say a locking pin, for automatically securing the leg of one longitudinal pole part in relation to the latter in the position of use when the stays are in the extended position. The invention also includes automatic means for locking or clamping the stays in their extended position. 35

With these and other objects in view the invention consists in the particular arrangement and construction of the parts as hereinafter described and shown in the drawings. 40

In the accompanying drawing one constructional example of the invention is represented:

Fig. 1 is a cross-section through two longitudinal pole parts showing the spacing means. 45

Fig. 2 shows the collapsed spacing means.

Figs. 3 and 4 show a stretcher in side elevation and plan respectively. These figures are on a smaller scale and do not show the 50 stretcher fabric.

Fig. 5 is an elevational view of the connecting means between the ends of two stays; Figure 6 is an elevational view of an end of the pole and the leg upon which it is supported; Figure 7 is a detail view of a pole end and leg therefor in folded position; Figure 8 is a substantially sectional view of a portion of the device showing the lug and plate at the end of the stay rod; Figure 9 is a substantially sectional view of a pole and adjacent portion of a stay in lowered position; and Figures 10 and 11 are side and plan elevational views, respectively, of the coupling between the abutting ends of the poles. 55

Referring to the drawings, the poles 1, 1', to which the stretcher fabric T is attached, each consist of two parts; an easily freed coupling G (Fig. 4), hereinafter more fully described, being provided for coupling up the two halves of each pole. Mounted on each pole part is a supporting leg 2. This leg 2 is arranged so as to fold over about a pin 3 and lie against the pole part, said pin being on a sleeve 5 fixed on the pole part. The legs 2 are preferably made of bent tubes with a 60 metal foot 6 at the lower end. The legs 2 have a pivot pin 8 near the top to which the end of a stay 9 or 9' is pivoted. The two stays 9, 9' are hingedly attached by a pin at 10. The stay 9 extends beyond the point 65 of attachment and has a sloping end 4. The sloped end 4 engages a spring-mounted ring or stirrup-catch 11 when the stays are clamped or locked in position. The ring 11 is pivoted on stay 9' and is forced over a 70 hump or safety projection 13 on the stay 9 against the action of a spring 12 positioned inside the stay 9' (which is tubular) when the spacing means is locked in the position of use (Fig. 1). The ring 11 is provided with 75 a projection 25 passing through a slot 26 of the tubular stay 9'. One end of the spring 12 abuts with one end on a pin 27 fixed in stay 9', the other end engages said projection 25, a disk 28 being interposed between the spring 12 and the projection 25. The spring 12 tends 80 to hold the ring 11 in the position shown in Fig. 5. The ring 11 locks or clamps the two stays 9, 9' automatically in their extended position, the projecting end 13 striking against 85

a projection 25 passing through a slot 26 of the tubular stay 9'. One end of the spring 12 abuts with one end on a pin 27 fixed in stay 9', the other end engages said projection 25, a disk 28 being interposed between the spring 12 and the projection 25. The spring 12 tends 90 to hold the ring 11 in the position shown in Fig. 5. The ring 11 locks or clamps the two stays 9, 9' automatically in their extended position, the projecting end 13 striking against 95

the free end of ring 11 as soon as the stays 9, 9' are brought in the position shown in Fig. 1. The ring 11 is first displaced against the action of spring 12 and snaps over the end 4 as soon as the stays 9, 9' attain their end positions (Fig. 1). The ring 11 passes over the catch 13 and retains the stays 9, 9' in their locked position; to free the ring 11 again before folding the stretcher some pressure has 10 to be applied to the ring 11 to pass it over the projection 13.

In addition there is provided on the stay 9' a cap 14. The cap 14, which is formed of a piece of sheet iron, is rigidly fastened to the 15 stay 9' and is provided with two spaced downwardly projecting lugs between which the end 4, of the stay 9 is inserted. Each of the stays 9, 9' is provided with a bolt 16. This bolt extends into a boring 17 (Fig. 7) on the folding leg 2 and also into a boring 18 provided in a downwardly extending lug 19 on the sleeve 5. Each stay 9, 9' has in addition a plate 20 which engages the lug 19 on the sleeve 5 when the spacing stays 9, 9' are extended and by this means the poles 1, 1' are spaced apart and the fabric T is drawn taut. The stays consequently maintain the legs 2 and the poles 1, 1' in the correct position. The load carried by the stretcher is taken up 20 by the stays 9, 9' through the plates 20. All the parts of the stretcher are now in their locked position.

Tubular components 30, 31 (Fig. 4) are rigidly secured to each half 1, 1' of a longitudinal pole for coupling up same. Inserted in the tubular component 30 is a fitting 32 which is, for example, welded in, whilst in the tube 31, a second fitting 33 is inserted and welded in. The end of the tubular member 30 is provided with a fitting 32 having spaced lugs between which a pin 34 is supported, the latter being disposed to enter slots 37 in the lugs of the fitting 33 as illustratively exemplified in Figure 10. The fittings 32, 33 have 45 outer abutting surfaces 38, 39 which engage one another when the pole parts are coupled up as shown in Figs. 8 and 9. The coupling between the two components is readily freed by lifting one of the fittings away from the other but the coupling is not liable to be freed unintentionally when the stretcher is in use.

What I wish to secure by U. S. Letters Patent is:—

1. Foldable braces and leg structure for 55 the separable longitudinal pole parts of a stretcher, comprising a sleeve fixed adjacent the end of each pole part and provided with a bracket projecting perpendicularly thereto and having an opening adjacent its outer end, 60 a U-shaped leg pivotally mounted at the end of one of its arms at a corner within said bracket, said arms having a cap for the ends of the legs provided with an opening disposed to register with the opening in the 65 bracket when the leg is swung to position per-

pendicular to the sleeve and pole part, and a locking member pivotally mounted between the arms of the leg and provided with a projection which projects into the registered openings in the bracket and leg cap to secure the leg in position perpendicular to the pole part. 70

2. Foldable braces and leg structure for the separable longitudinal pole parts of a stretcher, as claimed in claim 1, in which the bracket and sleeve are rigidly secured together by a web projecting transversely of the sleeve and longitudinally of the bracket along the side thereof adjacent the pivotal connection with the leg. 75

3. Foldable braces and leg structure for the separable longitudinal pole parts of a stretcher, as claimed in claim 1, in which the locking member comprises a socket to receive the end of a stay rod forming part of the stretcher frame and a splayed end comprising three parts, one thereof carrying the pivotal connection with the bracket, the intermediate projection curved about the pivotal connection of the other part as a center and forming the said projection to be inserted in the openings of the bracket and leg cap, and the third part being a shoe projecting perpendicular to the axis of the socket and stay rod and forming a stop abutting the bracket 95 when the leg is swung to position of use and the curved part is in locked position in said openings. 90

In witness whereof I affix my signature.

ERNST WEBER-STIERLIN.
